UNITED STATES PATENT OFFICE.

LOTTIE A. MITCHELL AND MARGARET ELLEN MITCHELL, OF HUNTINGTON, INDIANA.

COMBINED HEMMER, TUCKER, AND CORDER.

SPECIFICATION forming part of Letters Patent No. 766,509, dated August 2, 1904.

Application filed July 20, 1903. Serial No. 166,301. (No model.)

To all whom it may concern:

Be it known that we, LOTTIE A. MITCHELL and MARGARET ELLEN MITCHELL, citizens of the United States, residing at Huntington, in the county of Huntington and State of Indiana, have invented certain new and useful Improvements in a Combined Hemmer, Tucker, and Corder; and we do declare the following to be a full, clear, and exact description of the invention, such as will enable others skilled in the art to which it appertains to make and use the same, reference being had to the accompanying drawings, and to the letters and figures of reference marked thereon, which form a part of this specification.

Our invention relates to attachments for sewing-machines, and has for its object to combine in one attachment a device for hemming, facing, quilting, tucking, cording, stitching bands, &c.

With this object in view our invention consists in the novel construction of the attachment, but particularly in the scaled bars.

Our invention also consists in certain other novel features of construction and in combination of parts, which will be first fully described and afterward specifically pointed out in the appended claims.

Referring to the accompanying drawings, which illustrate our invention in position for some of its uses, Figure 1 is a perspective view of the attachment secured to a machine and acting as a tucker. Fig. 2 is a perspective view of the attachment acting as a corder. Fig. 3 is a perspective view showing the attachment acting as a hemmer. Fig. 4 is a perspective view of presser-bar-attaching piece. Fig. 5 is a sectional view taken through bar 1 and presser-bar-attaching piece 8. Fig. 6 is a perspective of sliding member or gage 3. Fig. 7 is a sectional view taken through bar 4 and sliding member or gage 3.

Like letters and numerals of reference indicate the same parts throughout the several figures, in which—

A indicates that portion of a sewing-machine sufficient to illustrate our invention, and B is the presser-bar, carrying the presser-foot C.

6 indicates our attachment, which consists 50 of the rear double or slotted bar 1, secured to the downwardly-inclined spring-link 7, to which is secured the slotted bar 4.

8 indicates the presser-bar-attaching piece, having its top surface cut out at 9 in order to 55 accommodate the slotted bar 1, which is secured thereto by the set-screw 2.

10 indicates the strap which passes around the front of the presser-bar and which is secured to the presser-bar-attaching piece 8 by 60 means of screws 11. A thread-cutter 12 is formed on said strap, as shown in Figs. 1, 2, and 3.

3 indicates the sliding gage, which is employed as in hemming, as shown in Fig. 3, 65 said gage having a tongue 13 on its top to enter the groove in the bar 4, and said gage is also provided with an extension 14, as shown in Fig. 6.

Secured to the spring-link 7 below the slotted bar 4 is a plate 15, which extends under and parallel with said slotted bar 4, as shown in Fig. 1. Secured to said slotted bar 4 by means of a set-screw 16 is a sliding gage 17, which is employed as in hemming, tucking, and cord- 75 ing, as shown in Figs. 1, 2, and 3, said gage having its bottom provided with a groove 18 for cording, as shown in Fig. 2.

Having thus set forth the several parts of our attachment, its operation is as follows: It 80 will be seen that the bar 1 is scaled from left to right and that the rear section 4' of bar 4 is scaled from "0" to the right and to the left, while the forward section 4" of said bar is scaled from left to right. The scale on 85 bar 1 and scale on forward section 4" of bar 4 are used in hemming, facing, and quilting, while scale on rear section 4' of bar 4 is used in tucking, cording, and stitching bands. For hemming, facing, and quilting the attachment is moved so that the bar 1 is set by set-screw over point "0" or "1," as shown in Fig. 3, and gage 3 is moved along bar 4 and set at "0" or "1," as shown at Fig. 3. Any width hem or facing desired can now be made, 90 the gage 17 being set on scale, as shown in Fig. 3, marking width of hem or facing, which may be one inch, two inches, &c., as

desired, the scales plainly indicating any width. For tucking, cording, and stitching bands the attachment is moved and the bar 1 is set as shown in Figs. 1 and 2. Gage 17 marks width of tucks and 3 the spaces. For instance, for a one-inch tuck the gage 17 is set at "1" on scale of rear section 4' of bar 4 and gage 3 at "2." This makes no space between the tucks; but any space desired can be 10 had by moving gage 3 and on any material without marking or basting. For cording the attachment is set as shown in Fig. 2 and gage 17 is set on scale of forward section 4' of bar 4 at a point corresponding with that of 15 scale of bar 1, while gage 3 marks space between the cords.

The plate 15 under bar 4 is for making tucks, as shown in Fig. 1, while the tuck is stitched down at the same time, the gage 17 20 marking width of tuck and gage 3 indicating the spaces.

Having set forth some of the operations of our attachment, it is unnecessary to go further into detail. We do not, however, wish to be 25 understood as limiting ourselves to the exact construction herein set forth, as various slight changes could be made therein which would fall within the limit and scope of our invention, and we consider ourselves clearly entitled to all such changes and modifications.

What we claim as our invention, and desire to secure by Letters Patent of the United States, is—

1. In a sewing-machine attachment, the 30 combination of a slotted scaled bar and means for securing the said bar to the presser-bar of a sewing-machine at any point along said

slotted bar, a slotted bar connected to said former slotted bar, and a plate secured under said latter slotted bar, between which plate 40 and said bar, the material to be hemmed or tucked passes, a slideable gage having an inwardly-extending projection carried on said latter bar substantially as described and for the purposes set forth. 45

2. In a sewing-machine attachment, the combination of a slotted bar and means for securing the same to the presser-bar of a sewing-machine at any point along said slotted bar, a slotted bar secured to said former 50 slotted bar, and a plate secured under said latter slotted bar, and a slideable gage carried on said latter slotted bar, and a slideable gage having a grooved bottom carried on said latter slotted bar, substantially as described and 55 for the purposes set forth.

3. In an attachment for sewing-machines, the combination of two slotted bars and means for securing the same to a sewing-machine at any point along one of said bars, a plate secured under one of said bars, between which plate and one of said bars the material to be hemmed or tucked passes, and two slideable gages carried on one of said bars, substantially as described and for the purposes set 60 forth. 65

In testimony whereof we affix our signatures in presence of two witnesses.

LOTTIE A. MITCHELL.
M. ELLEN MITCHELL.
